UNITED STATES PATENT OFFICE.

JOSEPH A. HOEGGER, OF JERSEY CITY, NEW JERSEY.

BOTTLE OPENER.

Application filed January 14, 1928. Serial No. 246,670.

My invention relates to improvements in bottle openers of the kind usually attached to a wall so as to be rigidly held in a permanent place, and to which the bottle and its closure are applied. My invention relates particularly to the combination with a cap removing bottle opener, and one object of the invention is to combine with such bottle opener a cork remover, preferably a corkscrew, which will be pivotally supported on the cap remover, will normally lie inconspicuously against the wall and will be covered in a manner to conceal the corkscrew and also prevent it from catching on various articles. The invention is further intended to provide a corkscrew and cover which will normally lie against a wall, but which can be swung out so that the cover will not interfere with the corkscrew, and the corkscrew can be conveniently operated. The invention is further intended to provide a convenient corkscrew and cover of this type irrespective of the particular fixture to which it is attached.

Reference is to be had to the accompanying drawings forming a part of this specification, in which similar reference characters indicate corresponding parts in all the views.

Figure 1 is a front elevation of the invention.

Figure 2 is a broken section on the line 2—2 of Figure 1.

Figure 3 is a cross section on the line 3—3 of Figure 1, and

Figure 4 is a side elevation showing the parts in position to permit the use of the corkscrew.

In the drawings I have shown a cap removing bottle opener 10 which has a base 11 adapted to be secured to the wall or other support. It frequently happens that bottles having caps and also corks need opening, and my invention provides for conveniently opening either kind. As illustrated the fixture 10 has on the under side a boss 12 which is slotted as shown at 13, and the shank of the corkscrew 15 is formed into an eye 14 which enters the slot and is pivoted on the pin 16. The corkscrew therefore, will normally hang perpendicularly, but can

be swung out to an angle as in Figure 4, so that it can be conveniently applied to a bottle cork, and of course the bottle will be swung to make the corkscrew enter the cork.

The boss 12 is preferably provided with a reduced extension 17 to which is pivoted the inner end part 18 of a hollow cover 19 which is pivoted as shown at 20, and preferably has its upper and inner part cut away as at 21 so that the cover can swing downward and inward and lie snugly over the corkscrew with the part 21 in close connection with the boss 12. Thus it will be seen that the cap remover 10 is always in position for use, that it can be used without recourse to the cork remover, and that if it is desired to remove a cork, the cover 19 and corkscrew 15 can be swung out to operative position and conveniently applied.

It will be seen, therefore, that both forms of bottle opener are in convenient proximity, and that either can be used without reference to the other; and it will be further understood that the cork remover can be pivotally supported on another type of fixture if desired, without affecting the invention. It will be seen that the cork remover can be differently supported, but the particular means shown is desirable because it is inconspicuous and convenient.

I claim:—

1. A wall bottle cork remover comprising a wall fixture, a cork removing element pivoted on the fixture, and a cover for the cork remover also pivoted on the fixture.

2. A wall bottle cork remover comprising a rigid fixture, a cork removing element pivoted on said fixture, a sheath for said cork remover also pivoted on said fixture and lying normally in a vertical position.

3. A wall bottle cork remover comprising a rigid fixture, a corkscrew pivoted on said fixture, a sheath for said corkscrew also pivoted on said fixture and adapted to drop by gravity to a position covering said cork screw.

In testimony whereof, I have signed my name to this specification this 13th day of January, 1928.

JOSEPH A. HOEGGER.
